[57] CLAIM

The ornamental design for a baseball bat rack, as shown and described.

DESCRIPTION

FIG. 1 is a top, front, and left side perspective view of a baseball bat rack showing my new design, the broken-line depiction of a baseball bat being for illustrative purposes only and forming no part of the claimed design; and

FIG. 2 is a bottom, rear, and right side perspective view thereof.

FIG. 2
